LEO J. GRUBMAN, OF BELLE HARBOR, NEW YORK

TOOL FOR MILLING EYE SOCKETS IN DOLL HEADS AND SIMILAR HOLLOW STRUCTURES

Application filed March 1, 1927. Serial No. 171,770.

This invention relates to tools for milling eye sockets in doll heads and similar hollow structures, and has for its primary object to provide a simple and novel means carried by the milling cutter for accurately sighting the eye opening through the head wall and positioning the edges thereof with respect to the center of rotation of the cutter.

More particularly, in one embodiment of my invention, I provide a rotating cutter head which is of substantially spherical form, the spherical surface of said cutter head having a sighting means thereon with respect to which one edge of the eye opening in the head wall is adapted to be positioned. Preferably, this sighting means is in the form of a number of spaced parallel circumferentially extending ribs any one of which may be selected in accordance with the angle at which the head is positioned and the head then manipulated or adjusted until one edge of the eye opening is positioned in proper relation to said rib whereby the operator will be apprised of the fact that the axis of rotation of the cutting head is in accurate registration with the minor vertical axis of the eye opening to thereby obtain an equal cutting action on the inner side of the head wall at the upper and lower edges of the eye opening and a symmetrical curvature of the concave wall of the socket. Thus, when an oscillating eye member is subsequently mounted and arranged in the socket, the center of the pupil thereon will accurately coincide with a vertical plane coincident with the minor axis of the eye opening.

It is a further general object of the invention to provide an improved sighting means for such milling tools which is exceedingly simple in its construction, efficient and reliable in practical use, and which makes it possible for the workman to very quickly obtain the necessary accuracy in the relationship of the cutter with respect to the opening through the head wall.

With the above and other objects in view, the invention consists in the improved tool for milling eye sockets in doll heads, and in the form, construction and relative arrangement of its several parts as will be hereinafter

more fully described, illustrated in the accompanying drawings, and subsequently incorporated in the subjoined claims.

In the drawings, wherein I have shown one simple and practical embodiment of the invention, and in which similar reference characters designate corresponding parts throughout the several views,—

Figure 1 is a side elevation showing one of the milling cutters and its operating spindle operatively positioned within a doll head, the latter being illustrated in section;

Fig. 2 is a fragmentary front elevation showing the sighting means on the cutters as co-related with the lower edges of the spaced eye openings in the front wall of the doll head;

Fig. 3 is a front elevation of the tool, the doll head being omitted;

Fig. 4 is a detail perspective view of the cutting blade, and

Fig. 5 is a similar view of the cutter head provided with my improved sighting means, with which the blade shown in Fig. 4 is adapted to be detachably assembled.

Referring in detail to the drawings, wherein I have partially illustrated a milling machine or tool of the type shown in my co-pending application Serial No. 32,301, filed May 23, 1925, 5 designates the stationary spindle rotatably mounted in a suitable bearing 6 fixed on the upper end of a standard 7, 8 designates the adjustable spindle rotatably mounted in the adjustable bearing 9 supported on the standard 7 whereby said spindles 5 and 8 may be spaced apart to various distances in accordance with the predetermined spaced relation between the eye openings in doll heads of different sizes. The adjusting means for the spindle 8 and its bearing 9 includes the manually adjustable screw 10 suitably mounted in the upper end of the standard 7. The several parts as just described are all substantially identical with the disclosure contained in my co-pending application, and in so far as the subject matter of this application is concerned, further detail description of the mounting and adjusting means for the tool spindles 5 and 8 is unnecessary to a clear understanding thereof.

It will however, become apparent as this description proceeds that the novel features of my present invention are not necessarily restricted to use in a tool of the multi-spindle type, but might also be utilized in connection with a single operating spindle and milling cutter. As shown, with the upper end of each of the spindles 5 and 8 a cutter head 11 is detachably connected in any suitable manner. 5 This cutter head as shown in Fig. 5 of the drawings is preferably provided with a cylindrical body portion terminating at one of its ends in a semi-spherical part generally indicated at 12. The cutter head is provided 10 with a longitudinally extending groove or slot 13 therein opening through the part 12 which is adapted to receive the cutter blade 14 shown in detail in Fig. 4. This blade is detachably fixed in the head 11 by means of 15 the screw shown at 15 and one end thereof is rounded and provided with arcuate cutting edges 16. The outer surface of the part 12 of the cutter head is provided with a series 20 of spaced parallel ribs 17 thereon substantially concentric with the axis of said cutter head. As will be noted from reference to Fig. 1 of the drawings, the cutting edges 16 of the blade 14 project outwardly beyond the edges of the ribs 17 so that said ribs do not 25 contact with the part operated upon by the cutter blade.

In the use of the tool as above described, the doll head shown at D is inserted over the two spindles 5 and 8, it being understood of 30 course, that the spindle 8 with its cutter head 11 has first been properly adjusted relative to the other spindle and cutter so as to space the centers of the semi-spherical end portions 35 12 of the two cutter heads in accordance with the known distance between the centers of the spaced eye openings in the front wall of the doll head. The doll head is then adjusted or manipulated until one of the ribs 17 on the part 12 of each cutter head bears substantially 40 the same relation to the lower edge of one of the eye openings d in the wall of the doll head as indicated in Fig. 2 of the drawings. The particular rib 17 which may be selected for the purpose of thus sighting the 45 milling cutters with relation to the edges of the eye openings determines the obliquely inclined position in which the head must be supported and held during the cutting operation. By the provision of these sighting ribs 50 on the cutter heads, it is apparent that in the rotation of the two milling cutters, the same amount of material will be cut from the inner side of the head wall at the upper and lower edges of each of the eye openings and 55 the concave surfaces of the two sockets thus formed will bear the same symmetrical relation with said edges of the eye openings. Of course, as the cutting action progresses, the selected sighting rib 17 will approach the 60 outer surface of the doll head wall at the 65

lower edge of the eye openings, and in this way the operator can determine when the sockets have been cut or milled out to the desired depth. Therefore, in all doll heads of the same size, the walls of the eye sockets 70 will bear substantially identically the same relation to the edges of the eye openings so that eye settings to be mounted in the doll heads will be freely interchangeable. When only a single spindle and milling cutter is 75 used, the operator merely shifts the head so as to position the cutter first at the rear side of one eye opening and then at the rear side of the other eye opening, properly sighting the cutter with relation to the edges of the openings in each instance as above described. It will be appreciated, however, that in either case, the milling operation may be very expeditiously and accurately performed and that the proper use of my new sighting means 80 for the milling cutters requires no high degree of skill on the part of the workman, but merely the exercise of good judgment.

In the foregoing description and accompanying drawings, I have described a preferred embodiment of my present improvements which has given excellent results in actual practice. Nevertheless, it is possible that the essential features of the invention might also be incorporated in various other alternative structures, and I accordingly reserve the privilege of resorting to all such legitimate mechanical changes therein as may be fairly incorporated within the spirit and scope of the invention as claimed. 100

I claim:

1. A milling tool of the character described including a rotatable spindle, a semi-spherical cutter head on one end of said spindle, a blade fixed in the cutter head in line with the spindle axis and having a cutting edge spaced from the periphery of said semi-spherical head, and said head having circumferentially extending sighting means on its periphery disposed at right angles to the axis 105 of rotation of the spindle. 110

2. A milling tool of the character described including a rotatable spindle, a semi-spherical cutter head on one end of said spindle, a blade fixed in the cutter head in line with the spindle axis and having a cutting edge spaced from the periphery of said semi-spherical head, and a sighting rib projecting from the surface of said semi-spherical cutter head and extending circumferentially thereof at right 115 angles to the axis of rotation of the spindle. 120

3. In a tool for milling eye receiving sockets in doll heads, a rotary spindle adapted to be positioned within a doll head through the neck opening thereof and having a semi-spherical cutter head at one of its ends, a blade fixed in said cutter head in line with the axis of the spindle and having its cutting edge positioned beyond the periphery of said cutter head for engagement with the doll head wall 125 130

at the inner side of one of the eye openings therein, and said head being provided with a sighting rib on its periphery extending circumferentially thereof at right angles to the axis of rotation of the spindle, one edge of the eye opening in the head wall adapted to be positioned relative to said rib to thereby dispose the major axis of the eye opening in definite relation to the axis of rotation of the cutter spindle.

4. In a tool for milling eye receiving sockets in doll heads, a rotary spindle adapted to be inserted within the doll head through the neck opening thereof, a semi-spherical cutter head fixed to one end of said spindle and provided with a plurality of spaced circumferentially extending sighting ribs on its periphery disposed at right angles to the axis of rotation of the spindle and with respect to which the edges of the eye opening in the doll head wall are adapted to be positioned to dispose the major axis of said eye opening in definite relation to the axis of rotation of the spindle, and a blade fixed in said cutter head positioned in a plane coincident with the spindle axis and having its cutting edge disposed beyond said sighting ribs.

In testimony that I claim the foregoing as my invention, I have signed my name hereto.

LEO J. GRUBMAN.
